APPARATUS FOR PACKING MECHANICALLY
GOODS OF EVERY KIND

Hans Lesch, Hannover, Germany, assignor to Firma Otto
Hansel Junior G.m.b.H., Hannover, Germany, a cor-
poration of Germany

Filed June 29, 1959, Ser. No. 823,386

6 Claims. (Cl. 53—195)

The present invention relates to an apparatus for mechanically packing goods of every kind. As is known, it is difficult to pack mechanically a greater number of individual pieces or bulk goods. In particular, this relates to candy, cookies, chocolate tablets, etc. when these are of irregular shape. To pack such articles, pre-fabricated cardboard boxes or packing bags have been used so far which were filled with the goods to be packed. Therefore, it was necessary to employ a machine producing the packing, a filling machine for the goods, and a suitable apparatus to close the pre-fabricated bags, boxes, or the like after they had been filled.

It is one object of the present invention to provide an apparatus for packing mechanically goods of every kind which avoids the described drawbacks.

It is another object of the present invention to provide an apparatus for mechanically packing goods of every kind, wherein at first the goods to be packed are filled into a box having at least one open side, whereupon a cut piece of wrapping material is placed around the filled box and closed except for the end fold, after which operation the box is pulled out of the wrapper while the goods are retained in the latter, which is then closed completely. Before or after the goods have been filled into the box it is possible to introduce cardboard shims or the like to stiffen the wrapper. In this way, every kind of goods may be packed in a convenient and quick manner, resulting in a packing of uniform and predetermined shape so that it is possible to sell the packed goods even in automatic machines. It is of particular advantage to pack sweets, fruit, food, bulk goods, as coffee, sugar, or the like, as well as individual pieces, as for instance ladies' stockings, sewing things, or small household articles in this manner.

It is also another object of the present invention to provide an apparatus for packing mechanically goods of every kind, wherein box conveying means carrying a plurality of boxes with at least one open end to a filling station, where the material to be packed is filled into the boxes, and a wrapping station where the wrapping material is placed around the filled boxes, are employed. Furthermore, a box remover is provided to pull the boxes out of the wrapping, when the latter is still open at one side, the goods to be packed being left in the wrapping, and the boxes being returned to the filling station, whereupon closing means close the wrapper completely.

It is a further object of the present invention to provide an apparatus for packing mechanically goods of every kind, wherein preferably, the boxes consist of stiff material, like metal, plastic, wood, or the like and have a U-shaped cross-section. Their ends are open and they are provided with a handle or the like at one side.

It is yet a further object of the present invention to provide an apparatus for packing mechanically goods of every kind, wherein the box conveying means and the return device may be formed of parallel endless belts, chains, and the like which connect the filling station and the

2

wrapping station and vice versa. A pushing member reciprocating at the end of the return device transverse to the direction of supply, pushes the empty boxes, one after another, onto the conveyor belt, chain, or the like passing through the filling station. Near the filling station the conveyor means may be inclined transverse to the direction of travel and slide along a rail or the like in a manner so that the side of the box provided with the handle is directed upwards and the lower end of the box covered by the rail. In this position, the box is ready to receive the goods to be packed. In front of and/or behind the filling station, feeding members may be provided for shims which later serve to stiffen the packing and which will be enclosed by the wrapping material.

The construction of the wrapping station is known. It may comprise a feeding member for the wrapping material and conventional folding and closing members or a folding tunnel or the like. A box remover is located in front of the members producing the end fold and consists of reciprocating grippers, hooks, or the like seizing the boxes and co-operating with an abutment or the like which is placed in front of the goods in the packing.

With these and other objects in view, which will become apparent in the following detailed description, the present invention will be clearly understood in connection with the accompanying drawings, in which:

FIGURES 1 to 10 are diagrammatic perspective views showing the different steps of the packing operations;

FIGS. 11A and 11B are jointly a side elevational view of a packing machine;

FIGS. 12A and 12B are jointly a top plan view of the machine, shown in FIGS. 11A and 11B;

FIG. 13 is a section along the lines 13—13 of FIG. 12;

FIG. 14 is a section along the lines 14—14 of FIG. 12A;

FIG. 15 is a section along the lines 15—15 of FIG. 12B;

FIG. 16 is a top plan view of the packing machine shown in FIG. 15; and

FIGS. 17 and 18 are sections similar to those shown in FIGS. 15 and 16, yet with several members in different working positions.

Referring now to the drawings, and in particular to FIGS. 1 to 10, the different packing operations are illustrated. Boxes *a* are employed which will be described later. The boxes are taken to the filling station where they receive a cardboard shim *b* or the like (FIG. 2). Then, the goods *c* to be packed are filled into the box *a*. It is of no importance whether the goods are individual pieces of the same or different shape and size or bulk goods. After inserting into the box the shim *b*, filling therein the goods *c* (FIG. 3), another reinforcing shim *d* is placed on top (FIG. 4). Now, the box *a* can be covered with a cut piece of wrapping material *e*. It is to be understood that several pieces of wrapping material may be employed. For better understanding and illustration, a transparent wrapping material, of cellophane for instance, has been used in this case. During the next operation (FIG. 5), the filled box together with the wrapping material is passed through a folding tunnel or through folding and closing members which fold the wrapping material *e* around the box *a* (FIG. 6). After that, the end fold is made by suitably arranged folding and closing members, so that eventually a packing *e*, closed at one end and open at the other end, is formed which also encloses the box *a*, as illustrated in FIG. 7.

During the following operation, removing means,

grippers, a hook, or the like, pulls the box *a* out of the open wrapper *e'* (FIG. 8), the goods contained in the box being retained in the wrapper by means of an abutment, a stop (not shown) or the like.

The boxes *a*, pulled out of the packing, are now returned to the filling station as indicated by an arrow in FIG. 8 while the wrapper *e'*, containing the goods to be packed and the two shims *b* and *d*, is forwarded to the closing station where, as shown in FIG. 9, the wrapper's open side is closed by folding or by compressing it in a manner illustrated in FIG. 10 so that the wrapper may be closed by folding or welding or clamping.

Preferably, the boxes *a* are of U-shaped cross-section, having a bottom *1* and upright side walls *2*. At one end the bottom *1* is extended to form a handle *3*, provided with an opening *4*. The handle *3* protrudes from the wrapper which is closed at one side, so that it is easy to pull the box out of the wrapper by means of grippers or the like reaching into the opening *4*. At the same time, a plate, abutment, or the like is introduced into the box to retain the goods in the wrapper when the box is pulled out.

Referring now to FIGS. 11A, 11B to 18 of the drawings, the boxes are moved by two parallel conveyors *5* and *6*, moving over rollers *7* in opposite directions, as indicated by arrows in FIG. 12A. Above the conveyors *5* and *6*, guide rails *8* are provided, guiding and centering the boxes *a* in each station. Furthermore, a feeding table *9* is arranged above the conveyors *5* and *6* for storing the goods *10* to be packed.

Near the filling station the conveyor *5* is inclined in a manner shown in FIG. 13, so that the side of the boxes *a* opposite the handle end rests against the guide *8*. In this position the goods *10* to be packed are easily filled into the box, as shown in FIG. 13. A shim *b* has previously been inserted into the box *a*. Said shim *b* is taken from a hopper *11* disposed at one end of the conveyors *5* and *6*, from which the shims *b* are ejected by means of a transversely reciprocating pusher member *12*. The same member *12* also pushes the empty boxes *a* from the return conveyor *6* to the conveyor *5* (indicated by an arrow in FIG. 12A).

The conveyor *5* transports the filled boxes to a rest *13*. Behind the rest a plunger *15* is arranged, controlled by a cam *14*. When moving up and down, the plunger lifts the filled boxes up to the level of slide rails *16*. A horizontally moving pusher *17* moves the boxes off the plunger *15* onto the slide rails *16*. Further transport of the boxes is through means of a transport chain *18* provided with suitable pins *19*, pawls, or the like. At the same time, another shim *20* is taken out of a stack or hopper *21* and placed on top of the packing.

The chain *18* takes the boxes *a* to another plunger *22* moving upwards, as is shown in FIG. 11B. Horizontally moving pliers *23* now draw a cut piece of wrapping material *24* over the box. An upper plunger *25* holds the wrapping material in place on the box. Both plungers *25* and *22* move upwards through a folding tunnel *26* so that during this operation the wrapping material *24* is folded around the box.

After the return of the lower plunger *22* a reciprocating folding member *29* produces the bottom fold, and then a horizontally moving pusher *27* forwards the box together with the wrapper onto a plate *28* so that through this action the opposite part of the wrapping material is also folded. Now, folding members *30* produce the face folds which are sealed or welded by means of a heating plunger *31*. At this moment, the different parts are in a position shown in FIG. 7. Three sides of the wrapper are completely closed and only the end with the handle *3* is open. From the open end of the wrapper a retainer *32* is introduced into the box, and at the same time a box-remover in the form of a hook *33* is inserted into the opening *4* of the handle *3*. During the next operation the hook *33* is moved in the direction of the arrow indicated in FIG.

12B, to pull the box out of the wrapper, while the contents of the packing are retained in the packing by means of the retainer *32*. This operation is illustrated in detail in FIG. 14.

5 The empty box pulled out of the wrapper by the hook *33* slides down a suitable chute *34* onto the conveyor *6* which returns the empty boxes to the filling station. On the other hand, the packings reach a conveyor *35*, provided with pawls, pins, or the like *36* and moving in the direction indicated by arrows in FIG. 11B. Now, the open end of the packing has to be closed. Conveniently, this is being done by closing means *37* which curl or compress the protruding part of the wrapper. It is to be understood that the packing may also be closed by folding and glueing or welding.

10 FIGS. 15 to 18 are detailed views of the closing operations. As can be seen, a lap *38* or the like is formed of the wrapper. A sealing ribbon *41* is drawn off a roller *39*, passes through transport rollers *40* and a pair 15 of scissors *42* and, by means of folding and pressing members *43*, is put around the lap *38* in the manner illustrated. To fold the sealing ribbon *41* in the form of a U, holders *44* and *45* are provided. If desired, a tear-off strip, a handle, a label, or the like may be inserted in the sealing ribbon *41* or in the lap *38*. Eventually, the closed packings *e'''* reach a conveyor *46* which forwards the packings for storage or further handling.

15 While I have disclosed one embodiment of the present invention, it is to be understood that this embodiment is 20 given by example only and not in a limiting sense, the scope of the present invention being determined by the objects and the claims.

I claim:

1. An apparatus, for wrapping mechanically goods, 25 particularly groups of goods of every kind, comprising a plurality of loose boxes open at least at one end, conveying means, a filling station, a wrapping station, a box removal station and a wrapper closing station, said conveying means feeding said loose boxes from said filling station through said intermediate stations into said wrapper closing station, said filling station being adapted to fill said boxes with said goods, said wrapping station including means for wrapping a length of material around each of said loose boxes individually, said box removal station including means for removing each of said boxes separately from the corresponding wrappers open at one end and retaining said goods in said wrappers, said wrapper-closing station including means for closing the open end of said wrapper, and said conveying means returning 30 said removed boxes to said filling station.

2. The apparatus, as set forth in claim 1, wherein said conveying means comprises a first endless conveyor band for feeding said boxes through said stations and a second endless conveyor band for returning said boxes to 35 said filling station, said conveyor bands being disposed parallel towards each other, a pusher member disposed at the end of said second endless conveyor band, taken in the direction of movement of the latter conveyor band, and reciprocating crosswise to the direction of movement 40 of said conveyor bands, said pusher member moving successively said returned boxes from said second endless conveyor band onto said first endless conveyor band, to enter again said filling station.

3. The apparatus, as set forth in claim 2 which includes a hopper member disposed in front of said filling station and adapted to receive a plurality of shims in superposed position.

4. The apparatus, as set forth in claim 2, which includes a hopper member disposed behind said filling station and adapted to receive a plurality of shims in superposed position.

5. The apparatus, as set forth in claim 1, wherein said boxes are of rigid material, of U-cross section and open 45 at their ends, and one of said ends has gripping means for

easy removal of said boxes from their corresponding wrappers.

6. The apparatus, as set forth in claim 2, wherein said first endless conveyor is inclined within the range of said filling station, and a feeding table disposed adjacent said conveying means for storing said goods to be packed, said boxes having their gripping means and their open end pointing upwardly towards said feeding table in order to receive said goods from the latter. 5
